Primary Examiner — Susan Bennett Hattan*Assistant Examiner* — Omeed Agilee(74) *Attorney, Agent, or Firm* — Foley & Lardner LLP(57) **CLAIM**

I claim the ornamental design for a vial for sampling assembly, as shown and described.

DESCRIPTION

FIG. 1 is a front perspective view of the claimed design; FIG. 2 is a front view of the claimed design of FIG. 1. The rear view, the left side view, and the right side view are identical to the front view; FIG. 3 is a top view of the claimed design of FIG. 1; FIG. 4 is a bottom view of the claimed design of FIG. 1; and, FIG. 5 is a cross-sectional view of the claimed design through the line 5-5 of FIG. 3.

1 Claim, 1 Drawing Sheet(56)
